UNITED STATES PATENT OFFICE.

SAMUEL SKALETZKY, OF NEW YORK, N. Y., ASSIGNOR TO SKALETZKY BROS. INC., OF NEW YORK, N. Y., A CORPORATION OF NEW YORK.

DESIGN FOR A FINGER RING.

Application filed March 24, 1927. Serial No. 21,319. Term of patent 3½ years.

To all whom it may concern:

Be it known that I, SAMUEL SKALETZKY, a citizen of the United States, residing at No. 1580 President Street, in the city of New York, county of Kings, and State of New York, have invented a new, original, and ornamental Design for a Finger Ring, of which the following is a specification, reference being had to the accompanying drawing, forming part thereof.

The figure is a perspective view of a finger ring constituting the design.

I claim:

The ornamental design for a finger ring as shown.

SAMUEL SKALETZKY.
